UNITED STATES PATENT OFFICE.

WILLIAM A. UTTZ, OF FORT WORTH, TEXAS.

LIFE-SAVING ATTACHMENT FOR LOCOMOTIVE-CABS.

1,147,464.

Specification of Letters Patent. Patented July 20, 1915.

Application filed February 16, 1915. Serial No. 8,518.

To all whom it may concern:

Be it known that I, WILLIAM A. UTTZ, a citizen of the United States, residing at Fort Worth, in the county of Tarrant and State of Texas, have invented certain new and useful Improvements in Life-Saving Attachments for Locomotive-Cabs, of which the following is a specification.

My invention relates to safety devices for escaping from locomotive engine cabs, and more particularly to a detachable carrier to be discharged from the engineer's cab in case of danger; and the object is to provide a carrier or protecting device into which the engineer can inclose himself instantly in time of danger and which device will be automatically detached from the cab and delivered to the ground or other place for the protection of the engineer.

The object is to provide a device which will inclose the engineer and protect him against falling on the ground or stones or other dangerous objects and which can be sealed air and water tight and provided with a valve which the engineer can operate. The same device is equally as available for the fireman as for the engineer.

The object is to protect the engineer and the fireman against fire and hot water or steam and to provide a ready means of escape from the engine cab.

One object is to provide a carrier or deliverer which cannot be crushed or will not be crushed in times of accident and danger. The carrier can be so arranged relative to the throttle valve lever and the angle cock of the air-brake system and the sanding devices that all these devices will be actuated by the falling of the carrier out of the cab. The engine may also be equipped with reversing devices which can also be actuated by the discharge of the carrier.

Other objects and advantages will be fully explained in the following description and the invention will be more particularly pointed out in the claims.

Reference is had to the accompanying drawings which form a part of this application.

Figure 1 is a front elevation of the carrier. Fig. 2 is a side elevation of the seat and certain actuating parts. Fig. 3 is a plan view of the carrier with the seat and its platform removed. Fig. 4 is a plan view of the seat platform, showing the air escapes. Fig. 5 is a detail view of the seat

releasing lever. Fig. 6 is a vertical section of the carrier and its lid and a side elevation of the seat. Fig. 7 is a detail view of the carrier detaching device, showing a slight variation from the device shown in Fig. 6 and Fig. 4. Fig. 8 is a detail of a device for starting the lid to close, the device being a variation from the device shown in the previous views. Fig. 9 is a detail view of one of the lid locking devices. Fig. 10 is a perspective view of a double carrier. Fig. 11 is a side elevation of a carrier provided with a different releasing device from the device previously shown. Fig. 12 is a side elevation of a carrier provided with a different releasing device and also provided with device for closing the throttle, devices for operating the sanding devices, and means for throwing on the air-brakes. Fig. 13 illustrates another releasing device, different from the releasing devices previously shown. Fig. 14 is a detail view of the key for detaching the releasing mechanism shown in Fig. 12. Fig. 15 is a detail view of the supporting bars for said releasing mechanism. Fig. 16 is a view of a portion of a carrier, showing how the carrier may be made to operate a reversing lever. Fig. 17 is a detail view of a discharging device varying the discharging device previously shown. Fig. 18 is a detail view of the releasing device shown in Fig. 13. Fig. 19 is a detail view, showing how the lid may be made to fit down on the carrier. Fig. 20 is a side elevation of a carrier, partly in section, illustrating how a cylinder may be rotatably mounted in the carrier.

Similar characters of reference are used to indicate the same parts throughout the several views.

The carrier herein shown includes a cylindrical body 1, provided with a bottom 2 and a lid 3, the lid being hinged thereto by hinges 4'. The bottom may be riveted to the body. The body may be provided with upholstering which can be held in place by a lining 4. The carrier is to be mounted in the cab in the most convenient position without interfering with the engineer's position or duties. The upper edge of the carrier is preferably mounted flush with the floor 5 of the engineer's cab which is braced by the bar 6. The carrier is mounted on hangers 7 and pins 8 which are operated as hereinafter set forth. The carrier is held against lateral displacement by hooks 9.

which are attached to the frame 10. The hangers 7 are provided with braces 11 and the frame piece 6 is provided with braces 12. The hooks 9 engage eyes 13 which are bolted to the carrier. An upholstered seat 14 is provided and mounted on a back 15 and platform 16. The seat is braced by the braces 17 and 18 and held in operative position by rods 20 which project into I-beam 21. Clutches 22 are attached to the back of the seat and engage the I-beam 21, as shown in Fig. 3 to guide the seat down in the carrier and back to positions shown in Figs. 1 and 6. Means are provided for holding the seat in these positions. Rods 20 are mounted in brackets 23 which are attached to the platform 16 and rods 20 are slidably mounted in the brackets 23. Spiral springs 24 are mounted on the rods and attached thereto at their inner ends and rest against the brackets 23 for seats. A T-lever 25 is pivotally connected to the back 15 of the seat and provided with handles 26. A T-bar 27 is pivotally connected to the lever 25 and chains 28 are attached to the bar 27 and extended down under pulleys or idlers 29 and attached to the rods 20. When the engineer wants to go down into the carrier, he pulls on the handles 26 and withdraws the rods 20 from the I-beams 21. The seat and the platform will instantly drop down in the carrier. Spring buffers 30 are attached to the bottom of the platform to prevent severe bumps on the bottom of the carrier. When the seat drops, several things take place. A spring lock 32 is attached to the back of the seat and this lock 32 will engage the top channel bar 31 inside of the carrier, the carrier being provided with channel bars for bracing purposes. Spring locks 33 will also engage the platform 16 and hold the same down. The lid 3 will close as soon as the seat disappears in the carrier. The seat is held back at the top by a latch 34 which is attached to a frame piece 35 and engages an eye or bracket 36 which is attached to the seat. When the seat drops, the eye 36 slips off the latch 34. Springs 37 and 38 are attached to the frame piece 35 and bear against the lid 3 and a hinged latch 39 is connected to the frame piece 35 and bears against the seat 15. The lid 3 bears against the latch 39 and thus the seat and the lid are rigid with each other until the seat drops. The latch 39 will swing upwardly and the springs 37 and 38 will throw the lid down as soon as the seat passes below the latch 39. When the lid comes down, it will strike the vertical rod 40 which effects a release of the carrier. A disk 41 is mounted on a shaft 42. A bar 43 is pivotally connected to the disk 41 and has slot 44 near the outer end. The vertical rod carries a wedge or spear 45 which enters the slot 44

and will thus force the rod 43 outwardly and at the rod 43 will turn the disk 41. The rods or pins 8 are pivotally connected to the pitman rods 46 which are pivotally connected to the disk 41. When the disk 41 is turned, the rods 8 will be drawn from the hangers 7 and thus release the carrier so that the carrier will drop out of the engineer's cab. When the carrier starts down, pins 47 which are rigid with the carrier will engage the pivoted bars 48 and these bars will force the carrier to swing outwardly and thus throw the carrier far enough to fall outside of the railway track. In order to prevent accidental dropping of the rod 40 a lug 49 is provided on the rod 40 and a spring 50 is attached to the inside of the cylinder 1 and provided with a lug 51 to support the lug 49 which is rigid with the rod 40. When the seat drops down in the carrier, it will strike the spring 50 and press the lug 51 from under the lug 49 and hold the same away until the seat is raised. Thus the lugs 49 and 51 will not interfere with the operation of the seat. When the seat is raised, the rod 40 is brought back to normal position. The lugs 51 and 49 will come to their normal positions automatically. When the rod 40 is raised, it will adjust the pins 8 to their normal or supporting positions. When the rod 40 is forced down, the spear 45 draws the pins 8 inwardly. Provision is made for locking the pins in the inward position. The bar 43 has a lug 52 rigid therewith. The rod 40 has a spear or wedge 53 rigid therewith turned in the opposite direction to the direction of the wedge 45. In the downward motion of the rod 40, the lug 52 will be drawn against the wedge 53 and thus lock the bar 43 stationary. When the rod 40 is drawn upwardly, the wedge or spear 53 will engage the lug 52 and thus force the pins 8 outwardly. Means are provided for locking the lid 15 down closed. Pivoted locks 54 are mounted in the lid by means of brackets 55. The lock is held in locking position by a spring 56 which is loosely connected to the lever end of the lock by a ring 57. The spring 56 is re-inforced by a spring 59. A bolt 58 extends through the lid from the outside and extends through the spiral spring 59 and through the spring 56 and is provided with a nut 60. A person within the carrier can release the lid by turning the nut 60 and forcing the spring 56 toward the lid. The nut 60 is provided with a handle 61. The lid can also be released from the outside. A wrench can be applied to the bolt 58 on the outside to turn the bolt to draw the lever end of the lock 54 in toward the lid. This would release the lock. The carrier may be provided with any simple valve 62 for the use of a person within the carrier to let in air when needed. The lid 15

may be provided with a weight 63 for making the lid heavy enough to force the rod 40 downwardly. The platform 16 may be provided with openings 64 to let the air pass through the platform as the platform is going down in the carrier. Without this provision, the air might impede the passage of the platform downwardly. The openings can be provided with screen coverings.

10 Rubber buffers 65 are mounted on the shaft 42 to coöperate with the spring buffers 30. The bearings for the shaft 42 are in a cup 66 which is attached to the false bottom 67 by means of flanges 68.

15 The swinging discharging arms 48 are prevented from swinging out of place by the pins 47, the hangers 7, and by guards 69.

A variation of the carrier releasing devices is shown in Fig. 7. Instead of the bar 43, an arm 70 is rigidly attached to the disk 41 and is loosely connected with a spring 71 which may be attached to the interior of the carrier 1. When the seat 14 drops down into the carrier, the platform 16 will bear the spring 71 and the arm 70 down and thus turn the disk 41 for operating the pitman rods 46.

20 A variation in the lid throwing means is shown in Fig. 8. A weight 72 may be used to throw the lid instead of the springs 37 and 38.

25 Fig. 10 illustrates one way of making a double carrier. The seats and the operating mechanism can be duplicates of the mechanism described. The carrier has two compartments instead of one. These compartments may have communication with each other by an opening through the partition 40 73 which separates the compartments,—the opening being indicated in dotted outline.

30 A variation in the carrier releasing devices is shown in Fig. 11. Lugs 74 are provided on the carrier 1. These lugs rest on the arms 11. The arms 11 are braced by the bars 75 which are pivotally connected to the arms 11 at their lower ends and hung on a bar 76 which is slidably mounted in double brackets 77 which are attached to the frame 45 10. The bar 76 simply projects through the brackets 77 on one side and at the other side extends over the top of the brackets and is provided with a lug 78 which projects back through the brackets 77. This is done in 50 55 order that a single movement of a single bar will release both arms 75 simultaneously. The arms or bars 75 project between the brackets 77 and the bar 76 and the lug 78 project through these bars as well as through 60 65 the brackets 77. Means are provided for moving the bar 76. These devices are shown in Figs. 11, 13, and 18. A spear or wedge 79 is mounted on each side of the carrier and supported on the bars 76 and on bars 80 65 70 which are attached to the cab frame. Small

brackets 81 may be attached to the frame to prevent displacement of the wedges. The bars 76 have slots 82 through which the wedges 79 operate to move these bars when the lid 3 strikes the wedges. The bars 80 70 have slots 83 into which the wedges 79 project so that the wedges will not yield in wrong direction. The bars 76 must move but the bars 80 must not move. Shoving the wedges 79 down will move the bars 76 out 75 of the ends of the bars 75 and thus let these bars swing down so that the carrier will drop downwardly. The bars 75 will drop down and rest on the brackets 84 and the guards 85 will prevent the bars 75 from falling forward in the cab.

80 85 Fig. 19 illustrates how the lid may be made to fit down on the upper edge of the carrier, making a water and air tight joint.

A different releasing mechanism is shown 90 in Figs. 12, 14, 15, and 16 from the releasing devices shown in figures previously described. A bar 86 is mounted in brackets 87 which are to be attached to the cab frame. The bar 86 is provided with roller bearings 88 and a slideable bar 89 is mounted on the roller bearings 88, it being understood that similar bars to bars 86 and 89 are mounted on each side of the carrier. The carrier is supported on the bars 89 by means of lugs 95 90 and ball bearings 91 which are mounted in the lugs 90. The bars 86 and 89 stand locked together by a key 92 which projects above the bar 89 and bends under and projects up through the bars 86 and 89. The 100 key 92 is held in place by a spring 93 which is attached to the bar 86. When the lid 3 falls it will knock the key 92 out of the bar 89 and on further motion of the lid, it will strike a wedge 94 which will move the bar 105 89 until the cut-out 95 registers with the cut-out 96 in the bar 86. The bearings 91 and the lugs 90 of the carrier will drop through these cut-outs and thus release the carrier so that the carrier will be discharged as above 110 described. The lid 3 is provided with lugs 97 and 98 for striking the key 92 and the wedge 94 respectively. If such releasing devices as here described are used, such releasing devices as are shown in previous figures would be dispensed with. The bottom of the carrier could be constructed differently. The bottom can be made concave, as shown in Fig. 12. The spaces 99 between the channel irons 31 may be inclosed to form 120 annular air spaces within the carrier to aid in making the carrier float. These spaces may be inclosed by sheet metal 100.

125 The brakes of the train may be applied by the falling of the carrier. The carrier is provided with a lug 101 and the handle 102 of the angle cock of a train line 103 may be projected into the path of the lug 101. When the carrier drops downwardly the lug 101 will turn the angle cock and thus 130

set the brakes. At the same time, the main throttle may be closed. A lug 105 is made rigid with the carrier. A hooked rod 106 is operatively connected with the throttle 107 and the hook thereon projects under the lug 105. The rod 106 is connected to a chain 108 which runs over an idler sprocket wheel 109 and this chain is connected to a bar 110 which is provided with a lug 111. 5 The bar 110 is suspended from a bar 112 which is mounted rigidly in brackets 113 so that the bar 110 is slidable. When the carrier drops downwardly, the lug 105 will pull on the bar 106 and thus draw the bar 10 110 so that the lug 111 will actuate the throttle 107 to close the same. When the carrier drops about nine inches, it will swing forward at the top so that the lug 105 will be disengaged from the rod 106. During 15 this operation, a sanding of the track will also be effected. A chain 114 is connected to the bar or rod 106 and runs over an idle sprocket wheel 115 and is connected to a bar 116 which is connected to the handle 117 of 20 the sanding device so that the sand will be discharged by the air on the tracks. 118 indicates a sanding device of ordinary construction.

Simultaneously with the above described 25 operations, a reverse lever 119 may be actuated to reverse the engine. A lug 120 is made rigid with the carrier. A lever 121 is pivotally mounted in the cab with one end projecting under the lug 120 and the other end positioned near the reverse lever 119. A bar 122 may serve as a guide for the lever 121. When the carrier drops downwardly, the lug 120 will actuate the lever 121 and this lever will actuate the reverse lever 119. 30 A variation in the carrier is shown in Fig. 20. A cylinder 123 is mounted in the carrier 1 and is made rotatable therein so that if the carrier turns over to any extent, the cylinder 123 need not necessarily be turned. 45 Ball bearings 124 are provided to prevent friction against the carrier 1. The asbestos lining 125, shown in Fig. 6 may be used in all the variations shown.

What I claim, is,—

50. 1. A safety attachment for the cabs of locomotives comprising a carrier mounted in the cab, an asbestos lining and an upholstered lining attached to the interior of said carrier, a seat supported on said carrier and adapted to descend therein, a lid hinged to the carrier, and means operatively connected to said seat and to said lid for closing the lid when the seat descends into the carrier.
60. 2. A safety attachment for the cabs of locomotives comprising a carrier mounted in the cab, hangers supporting said carrier in the cab, a seat supported on said carrier, means for releasing said seat for dropping the same in said carrier, a lid hingedly con-

nected to said carrier, means operatively connecting said seat and carrier whereby said lid is automatically closed by said seat when the seat drops, and releasing devices automatically actuated by the falling of 70 said lid for releasing said hangers.

3. A safety attachment for the cabs of locomotives comprising a carrier, hangers supporting the carrier in the cab, means for discharging the carrier from the cab, and 75 means operatively connecting said carrier with the angle cock of the train line of the air-brake system whereby the emergency brakes will be thrown on when said carrier is discharged from the cab.

4. A safety attachment for the cabs of locomotives comprising a carrier, hangers supporting the carrier in the cab, means for discharging the carrier from the cab, and means operatively connecting the carrier 85 with the throttle of the locomotive for automatically closing the throttle when the carrier is discharged from the cab.

5. A safety attachment for the cabs of locomotives comprising a carrier, hangers supporting the carrier in the cab, means for discharging the carrier from the cab, and means operatively connecting the carrier with the sanding devices of the locomotive for operating the sanding devices when the 95 carrier is discharged from the cab.

6. A safety attachment for the cabs of locomotives comprising a carrier, hangers supporting the carrier in the cab, means for discharging the carrier from the cab, and 100 means operatively connecting the carrier with the throttle and with the sanding devices of the locomotive for automatically closing the throttle and operating the sanding devices when the carrier is discharged 105 from the cab.

7. A life saving attachment for the cabs of locomotives comprising a carrier, hangers supporting the carrier in the cab, means for discharging the carrier from the cab, and means operatively connecting the carrier and the reversing lever of the locomotive for automatically actuating the reversing lever on the discharge of the carrier from the cab.

8. A life saving attachment for the cabs 115 of locomotives comprising a carrier, a lid hingedly connected thereto, means for closing said lid, and combined hangers and releasing devices operatively connected to the cab and to the carrier for automatically 120 discharging the carrier from the cab, being actuated by said lid when it falls.

9. A life saving attachment for the cabs of locomotives comprising a carrier consisting of an outer cylinder and an inner cylinder rotatable in the outer cylinder, a seat mounted on said carrier and adapted to descend therein, and means for discharging the carrier from the cab.

10. A life saving attachment for the cabs 130

of locomotives comprising a carrier consisting of an outer cylinder and an inner cylinder rotatable in the outer cylinder, a seat mounted on said carrier and adapted to descend therein, a lid hingedly connected to said carrier and operatively connected to said seat for automatically closing the lid when the lid drops, and means automatically actuated by said lid for discharging the carrier from the cab.

11. A safety attachment for the cabs of locomotives comprising a carrier mounted in the cab, a seat supported on the carrier and adapted to descend therein, a lid hingedly connected to the carrier and operatively connected to said seat for closing the lid when the seat drops, and means connected with the carrier and means connected with the lid for automatically locking the lid to the carrier when the lid falls.

12. A safety attachment for the cabs of locomotives comprising a carrier mounted in the cab, a seat supported on the carrier and adapted to descend into the carrier,

means for closing the carrier, and means for automatically locking the seat in the carrier when the seat descends therein.

13. A life saving attachment for the cabs of locomotives comprising a carrier mounted in the cab, a seat supported on the carrier and adapted to descend therein, means for closing the carrier, and yielding buffers for said seat to prevent pounding against the bottom of the carrier.

14. A life saving attachment for the cabs of locomotives comprising a carrier mounted in the cab, a seat supported on the carrier and adapted to descend therein, means for closing the carrier, and valves in the carrier for the use of an occupant of the carrier.

In testimony whereof, I set my hand in the presence of two witnesses; this 13th day of February, 1915.

WILLIAM A. UTTZ.
